UNITED STATES PATENT OFFICE.

JEAN F. WEBB, SR., OF NEW YORK, N. Y.

SAFETY APPARATUS FOR SUBMARINES.

Application filed May 3, 1924. Serial No. 710,748.

To all whom it may concern:

Be it known that I, JEAN F. WEBB, Sr., a citizen of the United States, residing at New York, in the county of New York and State of New York, have invented a new and Improved Safety Apparatus for Submarines, of which the following is a specification.

This invention relates to safety apparatus for submarines and has for its object to provide means for facilitating the quick relief and rescue of imprisoned crews of submarine vessels that have been accidentally sunk, by injury due to collision, or mechanical failure, and cannot rise again to the surface of their own power.

In emergencies of this kind, the very first essential is to provide means for obtaining a constant supply of fresh air, that life within the sunken vessel may be sustained. The second essential is to provide some means of indicating to relief parties seeking to rescue the victims and salvage the vessel, the location of such vessel; for in many cases the tides and cross-currents beneath the water's surface carry such submerged vessels so far from the place of sinking that it is very difficult and often impossible to locate their positions so that such rescue and salvaging may be effected.

Therefore, in its more detailed nature, the invention seeks to provide float structures releasable from the sunken submarine and equipped to provide means for supplying air to the interior of said sunken vessel and for providing a means for readily locating the position thereof and for aiding in the salvaging of the same. One said float is releasable from within the submarine and is adapted to carry to the surface therewith a relatively light-weight cable to which is secured a much heavier salvage cable, too heavy to be carried to the surface by said float but readily located and brought into function by reason of such light-weight cable and float connections. The supplying of air to the victims and the signalling of the wreck position being more essential than its salvaging, a specially constructed float is provided to carry signalling and air supplying devices to the water's surface. This

float is constructed to make possible its ejection from the torpedo tube of the vessel, such means of construction and manner of ejection rendering impossible the fouling of the float by accumulations of sea-weed or the like. Obviously, however, this feature of the invention may be employed in both float structures if desired.

The invention further resides in those novel details of construction, combinations and arrangements of parts, all of which will be first fully described, particularly pointed out in the appended claims, and illustrated in the accompanying drawings, which illustrate one practical adaptation of the invention, and in which:

Figure 1 is a diagrammatic side view illustrating the active relation of the parts of the invention.

Figure 2 is a side elevation of the torpedo buoy.

Figure 3 is an enlarged detail longitudinal section of the nose end of the torpedo buoy.

Figure 4 is an enlarged detail longitudinal section of the base end of the torpedo buoy.

Figure 5 is a detail longitudinal section of the air line carrying reel and connections.

Figure 6 is a detail sectional view illustrating the salvage buoy and connections therefor.

Figure 7 is a cross sectional view illustrating a sealing gasket feature cooperative with the air line in preventing leakage of water throughout the torpedo tube outlet.

Figure 8 is a cross section taken on the line 8—8 on Figure 7.

Figure 9 is a horizontal section taken on the line 9—9 on Figure 7.

Figure 10 is a cross section taken on the line 10—10 on Figure 2.

Figure 11 is a view similar to Figure 9, the air line being shown removed and a closure plug inserted in lieu thereof.

In the drawings, in which like numerals of reference indicate like parts in all the figures, 1 generally designates the submarine upon which the invention is shown as operatively applied, it being understood that the said invention is applicable in cooperation

with any of the common types of such vessels in use today. The torpedo tubes of the vessel are indicated 2 and the operating compartment is designated 3.

- 5 The invention embraces the provision of a torpedo float 4 so constructed and connected as to be adapted for being ejected from one of the torpedo tubes 2 of the vessel to rise to and remain on the water's 10 surface there to signal and indicate the position of the sunken vessel to which it is attached, and a salvage float 5 releasably secured to the deck structure of the submarine by operation of mechanism operable from 15 within the compartment 3 to enable the same to rise to and remain on the surface of the water to aid in indicating the position of the sunken vessel and, by reason of its peculiar connections therewith, to provide means 20 whereby the sunken vessel may be salvaged or for effecting a great aid in such salvaging. The peculiar construction of these devices and the means for connecting them in operable cooperation upon the submarine, 25 so as to provide a really practical submarine safety apparatus, constitute further features of the invention as will soon be apparent.

The float 4 is a torpedo shaped float or buoy constructed to comprise a copper shell 30 6, fitted or covered on the outside with narrow strips or staves 7 of a buoyant wood, (like balsa wood, which is almost as buoyant as cork), to protect the copper shell from injury or crushing at the instance of wave 35 dashed flotsam, and to greatly add to the buoyant nature of the float as a whole when in the water.

This wood covered float is to be made the proper size and shape to readily fit within 40 the torpedo tubes of the vessel so as to adapt the same for being ejected from the respective one thereof in the same manned employed to discharge torpedoes therefrom. While the float is particularly designed for 45 being compressed-air-ejected, it should be understood that ejection by explosive agencies and by hand are embraced in the conceptions of which the present is a disclosure.

At the top, the torpedo shaped float 4 is 50 provided with a conical metal hood or nose 8 to facilitate the passing thereof through any obstructions, such as sea-weed or the like in rising to the surface when ejected from the submarine, and for a secondary 55 purpose in protecting the lights and check valves placed on the top end of the float, and hereinafter referred to in detail.

Extending entirely through the hollow float is a metal air pipe 9 to the lower end 60 of which is firmly connected, and safely secured, as at 10, the upper end of a flexible wire covered air line 11 adapted to be carried to the surface by the buoyancy of the rising float when it is ejected, or released, 65 from the interior of the submarine. The

lower end of the air line remains in communication with the interior of the submarine, and when connected to any suitable air-pump located therein will be operative to draw in a constant supply of fresh air 70 from the surface, or, by reversing the action of the air pump, the foul air generated in the submarine can be forced out through it. In this manner perfect ventilation of the interior of the vessel may be had through 75 the one air line.

The upper end of the air line 11 extends through the top of the float a short distance, and to it are attached two check valves 12-13 in the manner shown in Figure 3. 80 The lower check-valve 12 is designed to open inwardly, so that fresh air can be sucked in through the same and down, through air line 11, into the interior of the submarine by means of the air-pump above mentioned. The upper check-valve 13 opens outwardly, and is used for blowing the foul air out of 85 the submarine through the air hose, when the action of the air-pump is reversed from a suction to a blowing action. The efficiency 90 of the pump can be greatly increased by attaching a wide-mouth funnel, or horn, (not shown) to the intake of the air-pump, when blowing out foul air.

A small insulated cable 14 of electric wires 95 is placed inside the entire length of the air line 11 and up into the metal pipe 9 where the wires pass through insulating bushings and are connected to heavy type electric signal globes inserted into suitable insulated 100 sockets carried by the head or top of the torpedo shaped float, as shown. When the float reaches the surface of the water the lower end of the wires are plugged into the electric battery connections of the vessel so 105 as to effect a lighting of the signal globe, and the float head, thus illumined, can be seen at night by rescue parties. This circuit can also be used in telephoning to the submerged crew by plugging suitable receiving and transmitting connections into the 110 sockets above and below.

When the float has reached the surface, the opening through which it has been ejected must be closed in the usual manner 115 as when torpedoes are used; but as the air line must remain extended outside the submarine while the float is on the surface, a small opening 15 must be provided in the usual tube closing doors 16 for it to pass 120 through. The closing doors 16 represent any type of opposing door torpedo tube closing mechanism found practical to employ.

To ensure the holding of this small opening water-tight, a solid rubber gasket 125 made in two sections, one carried by each of the opposing tube closure slide doors 16, as at 18, is provided and adapted to surround the air hose and close it tightly against leakage, see Figures 7 and 8. 130

To make the air line as light as possible, so it can be lifted easily by the float 3, it should be made of the best quality of rubber. The wire casing wrapped around 5 it can be made of aluminum wire, as it is much lighter in weight than copper or iron wire, and need be only of sufficient size to prevent the water pressure from squeezing the sides of the air hose together so air 10 cannot pass freely through the same to the vessel.

The air line 11 is preferably wound around a reel or drum 19, such as is shown in detail in Figure 5 of the drawings, in 15 order to facilitate the proper launching or ejecting of the torpedo float in a systematic and practical manner without danger of tangling or breaking of the air line connections. The drum has a hollow chamber 20 with which the submarine end of the air line is in communication by reason of its connection in the hub 21 of the drum provided for that purpose.

The drum 19 includes a pair of hollow 25 trunnions 22 adapted to have bearing in suitable supporting bearings 23 to facilitate free rotation of the said drum. A suitable hand brake 24 may be provided to effect perfect control of the paying out of the air 30 line 11, if desired.

One of the drum trunnions 22 is provided with a swivel coupling union connection 25 to which the line connection 26 of the pump above referred to may be readily connected, and the other such trunnion is provided with a contact plug 27 with which the electric-wires-carrying cable 14 connects, thus forming a convenient connection for the connector plug 28 which may 40 be connected, through the conducting connection 29, with the submarine batteries, as and for the purposes above referred to.

The drum may also be provided with a suitable turning crank 30 whereby the same 45 may be turned to effect a reeling in of the air line 11 when desired.

Before the torpedo shaped float 4 is launched or rather ejected from the submarine to rise to the surface, the air pump 50 should be attached to the hollow drum by connecting the pump line 26 with the union 25, and the air forced thereinto, and through the same into and through the coils of the air line 11, throughout its length, 55 until it reaches a safe inside pressure.

It should be understood that the great 60 pressure of the water on the check valve 13 will hold the same closed against the air pressure from within. By keeping the air pump continuously working while the float 65 is rising to the surface the air and water pressure can be substantially balanced so that the tendency of water to enter the check valve 12 is reduced to the minimum. The slight difficulty of water entry is negligi-

ble and present only during the time of rising to the surface of the float and the tendency decreases, in degree as the float rises. Any slight amount of water entering the line 11 will be quickly expelled by air pressure as the float nears the surface of the water.

This filling of the air line with the slightly compressed air will add to its buoyancy in rising, will keep it expanded from the inside to resist water pressure, and will effectively prevent water from entering the check valves while rising. When the float reaches the surface, the action of the air pump is promptly reversed into a suction 80 action, which will at once replace the compressed air with fresh air from the surface; and this current of fresh air will keep the hose expanded from surface to vessel.

Obviously any type of double acting 85 pump may be used, preferably one of the hand operated types, and as the exact structure thereof forms no feature of this invention the pump is but diagrammatically illustrated and indicated by the numeral 31.

The "balsa" wood staves 7 should be beveled on the sides, to insure a smooth round surface, and they can be bound with thin brass or aluminum hoops 32. The staves should be not less than an inch or more in thickness, to assist the buoyancy of the float in sustaining the air hose. This float can be stored with other torpedoes until needed in any emergency.

When the pump action has been reversed 100 and fresh air thus drawn in to revive and sustain the crew through check valve 12 and air line 11, the "secondary" essential of safety becomes very important. It is not only necessary to indicate on the surface the location of the submerged vessel, but to assist, if possible, in raising it quickly to the surface.

With these two objects in view, I have designed the other form of hollow copper float 110 5 having a small light cable 33 attached to it that the float can easily carry to the surface. This small cable has its lower end firmly attached to a large powerful cable 34 that can greatly assist in the raising of the vessel, as the lower end of it is securely fastened as at 35 to the interior frame work so that it can withstand lifting strains.

When the rescuing ship reaches the location indicated by the buoy, they will first proceed to lift the buoy on board to secure the small cable 33; then wrap it around a winch or capstan on the ship, which will wind it up to bring the large cable 34 on board. This large cable will then be attached to the capstan, and slowly and carefully will be tightened to a lifting strain on the submerged vessel. If it is one of the smaller models, it may be brought to 125 surface gradually; but with larger ones,

that will require several cables to lift them, the secured cable will be of greater assistance to the divers in attaching others.

This location buoy is carried on deck by frame 36 or cradle of naval bronze, and provided with securing arms 37, pivoted at 38 and connected by moving elements so constructed and arranged that they can be thrown open from the interior of the vessel 10 by the crew, to free the buoy from the cradle so it can float upward to the surface taking with it the small cable 33 to the position shown in Figure No. 1. The cables are coiled in a "well" 39 mounted upon the 15 deck. The mechanism for opening the cradle by the imprisoned crew from the interior consists of swivel screw bearings 40 mounted in the lower ends of the arms 37, a double thread operating screw 41 having 20 a gear 42 secured thereupon, and adapted to have rotation imparted thereto by the gear 43 adapted to be rotated by the hand wheel 44 within the submarine. Placed just behind the conning tower it will present little 25 resistance in motion.

Backer plates 45 engage the soft rubber gasket members 17 and, when engaged by the forcing screws 46, threaded through the brackets 48 provided for that purpose and 30 secured upon doors 16, serve to compress the said members 17 and to force them in tight relation around the air line 11 and in their relation with the door crevice to effectively prevent water leaking into the compartments of the submarine.

A supporting bearing member 49 may be provided and be chain connected at 50 to the float 4 to so support the air line 11 as to greatly aid in preventing flexing thereof at 40 a point which would cause an early breaking thereof.

Copper end plates 51 may be provided, one for each end of the float 4, and be bolted and soldered thereto to strengthen the float 45 and render it less liable to injury by shock or leakage.

By reference to Figure 11 of the drawings, it will be seen that a suitable solid cylindrical plug member 52 may be inserted through the aperture 15 in the doors 16 to be acted upon by the gasket halves 17 to provide a water-tight joint when the air line 11 is not in position therebetween.

It will also be observed from Figures 2 55 and 4 of the drawings that a rubber gasket ring 53 may be provided and secured to the float 4 at the lower end thereof (rear end when being ejected) so as to effectively seal the torpedo tube and facilitate the ejection of the float therethrough, by compressed air, as is usual in torpedo ejection.

It is believed that with the inexpensive equipment described, the lives of a crew, and the submarine itself, can always be saved. 60 Its use will also remove the dread of sub-

marine service, in both officers and men in naval service.

What I claim is:

1. The combination with a submarine vessel having a torpedo tube, of a float adapted 70 to be ejected through the torpedo tube, a hollow cable connected with the float and terminating within the submarine vessel to lead air thereinto from above the water surface, check valves oppositely operable to 75 control the hollow passage of the cable, and a nose having windows and being secured to one end of the float over the said valves.

2. In submarine safety apparatus, a torpedo shaped float adapted for being ejected 80 from the torpedo tube of a sunken submarine, signaling devices mounted on the float, means for electrically connecting the signaling devices with a source of electric energy within the sunken submarine, a securing line through which the electrical connections pass and which is secured to the float and to and within the sunken submarine, the said line being hollow to permit 85 passage of air therethrough, check valves oppositely operable to control the hollow passage, and a metal reinforce nose having windows and being secured to one end of the float over the signaling devices and the 90 valves.

3. The combination with a submarine vessel, of a float adapted to be released from the submarine, a hollow cable connected with the float and terminating within the submarine vessel, check valves oppositely operable to control the hollow passage of the cable, and a double acting pump adapted to effect a breathing in and out of fresh and foul air into and out of the submarine vessel 100 through the said cable.

4. The combination with a submarine vessel having a torpedo tube, of a torpedo shaped float adapted to be ejected from the torpedo tube of the submarine, a hollow cable connected with the float and terminating within the submarine vessel check valves operable to control the hollow passage of the cable, and a double acting pump adapted to cooperate with the air passage and valves to fill the said passage with partially compressed air to prevent cable collapse and water induction during ejection of the float and for effecting breathing in and out of fresh and foul air into and out of the submarine vessel after the float has 110 reached the surface of the sea.

5. In submarine safety apparatus, a torpedo shaped float adapted for being ejected 115 from the torpedo tube of a sunken submarine, signaling devices mounted on the float, means for electrically connecting the signaling devices with a source of electric energy within the sunken submarine, a securing line through which the electrical connections pass and which is secured to the 120

float and to and within the submarine, and a rubber packer gasket surrounding the rear end of the float to facilitate its ejection from the torpedo tube by compressed air.

6. In submarine safety apparatus, a torpedo shaped float adapted for being ejected from the torpedo tube of a sunken submarine, signaling devices mounted on the float, means for electrically connecting the 10 signaling devices with a source of electric energy within the sunken submarine, a securing line through which the electrical connections pass and which is secured to the float and to and within the sunken submarine, the said line being hollow to permit 15 passage of air therethrough, check valves oppositely operable to control the hollow passage, a metal reinforce nose having windows and being secured to one end of the 20 float over the signaling devices and the valves, and a rubber packer gasket surrounding the rear end of the float to facilitate its ejection from the torpedo tube by compressed air.

25. 7. The combination with a submarine vessel having a torpedo tube and opposing slideable doors to close the same, of a float adapted to be ejected through the torpedo tube, a hollow cable connected with the float passing through the tube and doors and terminating within the submarine vessel to lead air thereinto from above the water's surface, opposing gasket members mounted upon the slideable doors, and means for forcing the 30 gasket members together over the cable to prevent water leakage.

8. The combination with a submarine vessel having a torpedo tube and opposing slideable doors to close the same, of a float 40 adapted to be ejected through the torpedo tube, a hollow cable connected with the float passing through the tube and doors and terminating within the submarine vessel to lead air thereinto from above the water's surface, opposing gasket members slidably carried by the doors, fixed brackets carried by 45 the doors, and screw elements passing through the brackets and acting against the gasket members to cause them to forcefully 50 oppose each other over the cable to prevent leakage of water.

9. In submarine safety apparatus, a torpedo shaped float adapted for being ejected from the torpedo tube of a sunken submarine, 55 signaling devices mounted on the float, means for electrically connecting the signaling devices with a source of electric energy within the sunken submarine, a securing line through which the electrical connections pass and which is secured to the 60 float and to and within the submarine, and a supporting bearing member for the cable being chain connected to the float bottom to surround the said cable at a point a short 65 distance from said float.

10. In submarine safety apparatus, a torpedo shaped float adapted for being ejected from the torpedo tube of a sunken submarine, signaling devices mounted on the float, means for electrically connecting the 70 signaling devices with a source of electric energy within the sunken submarine, a securing line through which the electrical connections pass and which is secured to the float and to and within the sunken submarine, the said line being hollow to permit 75 passage of air therethrough, check valves oppositely operable to control the hollow passage, a metal reinforce nose having windows and being secured to one end of the float over the signaling devices and the valves, a rubber packer gasket surrounding the rear end of the float to facilitate its ejection from the torpedo tube by compressed air and a supporting bearing member for the cable being chain connected to the float bottom to surround the said cable at a point a short distance from said float.

11. The combination with a submarine vessel having a torpedo tube, of a torpedo shaped float adapted to be ejected through the torpedo tube, the said float including a wooden stave built casing, metal bands for embracing the staves, a metal reinforce nose spaced from the staves to provide windows, 90 a hollow cable connected with the float and to and within the submarine vessel to lead air thereinto from above the water's surface, and check valves housed within the nose and in communication with the cable 95 passage to control the same.

12. The combination with a submarine vessel having a torpedo tube, of a torpedo shaped float adapted to be ejected through the torpedo tube, the said float including a 100 hollow metal shell, wooden staves encasing the shell, metal bands embracing the staves, a metal reinforce cap over each end of the float, a metal reinforce nose spaced from an end of the float to provide windows, a hollow rigid conductor tube passing longitudinally through the float, a flexible hollow conduit and securing cable secured to and communicating with the rigid tube and to and within the submarine vessel, signaling devices mounted on the float and housed by the nose, means for electrically connecting the signaling devices within the submarine, and check valves oppositely operable to control the hollow passages of tube and line 110 and housed by the nose.

13. The combination with a submarine vessel having a torpedo tube, of a torpedo shaped float adapted to be ejected through the torpedo tube, the said float including a 115 hollow metal shell, wooden staves encasing the shell, metal bands embracing the staves, a metal reinforce cap over each end of the float, a metal reinforce nose spaced from an end of the float to provide windows, a hol- 120

- low rigid conductor tube passing longitudinally through the float, a flexible hollow conducting and securing cable secured to and communicating with the rigid tube and to and within the submarine vessel, signaling devices mounted on the float and housed by the nose, means for electrically connecting the signaling devices within the submarine, check valves oppositely operable to control the hollow passages of tube and line and housed by the nose, and a supporting bearing member for the cable chain connected to the float bottom to surround the said cable at a point a short distance from said float.
14. The combination with a submarine vessel having a torpedo tube, of a torpedo shaped float adapted to be ejected through the torpedo tube, the said float including a hollow metal shell, wooden staves encasing the shell, metal bands embracing the staves, a metal reinforce cap over each end of the float, a metal reinforce nose spaced from an end of the float to provide windows, a hollow rigid conductor tube passing longitudinally through the float, a flexible hollow conducting and securing cable secured to and communicating with the rigid tube and to and within the submarine vessel, signaling devices mounted on the float and housed by the nose, means for electrically connecting the signaling devices within the submarine, check valves oppositely operable to control the hollow passages of tube and line and housed by the nose, and a rubber gasket surrounding the end of the float opposite the nose to facilitate compressed air ejection of the float.
15. The combination with a submarine vessel having a torpedo tube, of a torpedo shaped float adapted to be ejected through the torpedo tube, the said float including a hollow metal shell, wooden staves, encasing the shell, metal bands embracing the staves, a metal reinforce cap over each end of the float, a metal reinforce nose spaced from an end of the float to provide windows, a hollow rigid conductor tube passing longitudinally through the float, a flexible hollow conducting and securing cable secured to and communicating with the rigid tube and to and within the submarine vessel, signaling devices mounted on the float and housed by the nose, means for electrically connecting the signaling devices within the submarine, check valves oppositely operable to control the hollow passages of tube and line and housed by the nose, a rubber gasket surrounding the end of the float opposite the nose to facilitate compressed air ejection of the float, and a supporting bearing member for the cable chain connected to the float bottom to surround the said cable at a point a short distance from said float.
16. The combination with a submarine vessel having a torpedo tube, of a float adapted to be ejected through the torpedo tube, a hollow cable connected with the float and terminating within the submarine vessel to lead air thereinto from above the water surface, and a hollow winding drum rotatably mounted within the submarine upon which the cable is reeled before float ejection, and from which it is payed out as ejected, and having a hub to which the cable may be secured to communicate with the hollow of the drum and hollow trunnions, a swivel pump-connecting union connected in one trunnion, and a brake for controlling rotation of the drum.
17. The combination with a submarine vessel having a torpedo tube, of a float adapted to be ejected through the torpedo tube, a hollow cable connected with the float and terminating within the submarine vessel to lead air thereinto from above the water surface, check valves operable to control the hollow passage of the cable, a hollow winding drum rotatably mounted within the submarine upon which the cable is reeled before float ejection and from which it is payed out as ejected, and having a hub to which the cable may be secured to communicate with the hollow of the drum and hollow trunnions, a swivel pump-connecting union connected in one trunnion, a brake for controlling rotation of the drum, and a double acting pump adapted to be connected to the connecting union of the drum to cooperate with the hollow thereof and the air passage and valves to fill the said passage with partially compressed air to prevent cable collapse and water induction during ejection of the float and for effecting breathing in and out of fresh and foul air into and out of the submarine vessel after the float has reached the surface of the sea.
18. In submarine safety apparatus, a torpedo shaped float adapted for being ejected from the torpedo tube of a sunken submarine, signaling devices mounted on the float, means for electrically connecting the signaling devices with a source of electric energy within the sunken submarine, a securing line through which the electrical connections pass and which is secured to the float and to and within the submarine, a salvage buoy mounted upon the submarine and releasable therefrom from within, a light weight cable adapted to be carried to the surface by the buoy, a heavy weight salvage cable secured to the light weight cable and to the submarine and adapted to be drawn to the surface thereby, a well mounted upon the submarine to house the cable when in normal wound condition, the said buoy including an annular flange, pivoted arms having gripping portions at their upper ends for engaging and holding the buoy by its flange, a frame on which the arms are pivotally mounted,

pivoted screw bearing heads mounted on the lower arm ends, a double threaded rod for engaging the heads to move the arms when rotated, and gear connections, and a hand wheel mounted within the submarine for moving the rod.

the vessel and having its lower end within the vessel, check valves oppositely operable to control the passageway of said duct and a pump adapted to effect a breathing in and out of fresh and foul air into and out of the vessel through said duct.

19. In combination with a submarine vessel, a hollow duct adapted to extend above

JEAN F. WEBB, Sr.
